(57) **CLAIM**

The ornamental design for an electric foot callus remover and accessory set, as shown and described.

DESCRIPTION

FIG. 1 is a top perspective view of an electric foot callus remover and accessory set showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is an enlarged view of a portion indicated with "9" in FIG. 1.

The dash-dash broken lines illustrate portions of the electric foot callus remover and accessory set that form no part of the claimed design. The dot-dash broken lines illustrate the boundaries of the enlarged detail views and form no part of the claimed design.

1 Claim, 9 Drawing Sheets
